COMBINED SINK AND STOOL

Filed Nov. 12, 1941

UNITED STATES PATENT OFFICE

2,339,647

COMBINED SINK AND STOOL

Fred William Meyer, Louisville, Ky.

Application November 12, 1941, Serial No. 418,815

11 Claims. (Cl. 4—187)

This invention is a novel improvement in kitchen sinks or the like, and the principal object thereof is to provide a combined sink and stool in which the longitudinal axis of the sink is disposed at substantially right angles to the drain board and projects out into the room beyond the drain board, which drain board may be disposed at one or both sides of the sink; also to provide a novel seat horizontally swingably mounted upon a standard disposed at either outer corner of the sink so as to be moved from an inoperative position under the sink into operative position in the L-shaped bay formed between the drain board and side of the sink, whereby the dishwasher or cook may be comfortably and conveniently seated, the seat being vertically adjustable on said standard so as to accommodate the height of the user.

I will explain the invention with reference to the accompanying drawing, which illustrates several practical embodiments thereof to enable others to adopt and use the same; and will summarize in the claims, the novel features of construction, and novel combination of parts, for which protection is desired.

In said drawing—

Fig. 1 is a top plan view of my novel sink showing a drain board at either side of the sink; also showing in full lines the swingable seat in position for use, and showing in dotted lines the inoperative position of the seat underneath the sink.

Fig. 2 is a front elevation thereof, showing in full lines one modification in which the upright supporting the swingable seat engages a socket therefor at one outer corner of the sink; and showing in dotted lines the upright swung to engage the socket at the other outer corner of the sink.

Fig. 3 is a vertical section on the line 3—3, Fig. 2.

Fig. 4 is a horizontal section on the line 4—4, Fig. 3.

Fig. 5 is a modification showing the use of a vertical upright for the seat, instead of the bent upright shown in Fig. 2.

As shown in Fig. 1, the sink preferably consists of a sink portion 1 having its longitudinal axis disposed normal to the wall, said sink being provided with drain boards 2 formed integrally with the sink and being disposed at either or both sides of the sink. Preferably the wall engaging portion of the sink is provided with a flange 3, and the ends and outer edges of the drain boards 2 are rolled as at 4, and the outer end and sides of the sink 1 are provided with aprons 5 in the cus-

tomary manner extending downwardly adjacent to or below the bottom of the sink as indicated in Fig. 2 to enhance the appearance thereof.

As shown, drain boards 2 are of considerably less width than the length of sink 1, so that the sink will project a substantial distance into the room or substantially beyond the rolled outer edges 4 of the drain boards 2, thus providing an L-shaped bay between the side of the sink 1 and the outer edge of the drain board 2 at either or both sides of the sink to accommodate a seat whereby the dishwasher or cook may conveniently sit and wash the dishes or prepare the food.

As shown in Figs. 2, 3 and 4, the seat is preferably mounted upon an upright or standard secured between the floor and the underside of the sink adjacent one or both outer corners thereof. The underside of sink 1 adjacent the drain board 2 is provided with a pocket 6 having a transverse rib 7 extending diametrically thereof at its inner end, said pocket 6 being adapted to receive the upper end of an upright 8 which is threaded as at 8a (Fig. 3) and carries a lock nut 9, the upper end of the upright 8 having diametrically opposed slots 8b adapted to accommodate the transverse rib 7 in the pocket 6. Upon the upright 8 at a convenient distance below the sink 1 is a vertically adjustable collar 10 for adjusting the height of the seat.

As shown in Fig. 2, the lower part of the upright 8 is offset inwardly so as to be disposed upon the longitudinal axis of sink 1, and the lower end is threaded as at 8c, the same carrying a lock nut 11, the lower threaded end of the upright 8 entering a socket in a pedestal 12 secured upon the floor of the room by screws 12a or the like.

In assembling the upright, the lock nuts 9 and 11 would be backed inwardly of the ends of the upright and the lower end of the upright inserted in socket 12, and the upper end of the upright inserted in pocket 6 with the slots 8b receiving the rib 7 so as to prevent the upright from turning, and the lock nuts 9 and 11 then threaded against the ends of the pocket 6 and the socket 12 to securely lock the upright in position.

Swingably mounted upon the upright 8 is an arm 13 having a T 14 at its inner end rotatably mounted upon the upright with its lower end resting upon the collar 10. The outer end of arm 13 carries a T 15 provided with coarse threads 16a engaging corresponding threads on a post 16, the upper end of which carries the seat 17, whereby rotation of the seat will raise or lower the same with respect to the arm 13. Arm 13 is of such length that when the seat 17 is swung into

operative position as shown in full lines in Fig. 1, the same will be disposed at a convenient distance from the apron 5 of the sink and the rolled edge 4 of the drain board, and arm 13 may be straight or curved as desired. Seat 17 is so disposed vertically that the arm and the seat may be swung under the sink as shown in dotted lines in Fig. 1 so as to be out of the way of the dishwasher or cook.

When the sink is provided with two drain boards 2 at opposite sides thereof, as shown in Fig. 1, the underside of sink 1 is also provided with a second pocket 18 similar in all respects to pocket 6 and disposed the same distance from the axis of the socket 12, so that if the seat 17 is to be disposed at the opposite side of the sink, all that is necessary is to swing the upright 8 so that it engages the socket 12 and the pocket 18 as indicated in dotted lines in Fig. 2 instead of with socket 12 and pocket 6 as shown in full lines in said figure; and thus the one upright 8 and socket member 12 will serve to mount the seat 17 at either side of sink 1.

Fig. 5 shows a modification in which straight uprights 19 may be utilized at either or both sides of the sink 1 in place of the curved upright 8, and in which the upper end of the upright 19 may be disposed nearer the side portions of the sink than is shown in Figs. 1 and 2. In this modification the sink is cast or formed with a fillet 20 disposed between the apron 5 and body of the sink 1 at either or both sides of the sink adjacent the outer corners thereof. In the underside of fillet 20 is a pocket 21 having a diametrically disposed rib 22 therein corresponding with the rib 7 shown in Fig. 3. The upper end of the upright 19 is provided with transverse slots receiving the rib 22, and the upper end is threaded as at 23 and carries a lock nut 24. The lower end of the upright 19 is threaded as at 25 and carries a nut 26 and a lock nut 27. Nut 26 is adapted to engage the threads of a floor plate 28 which is secured by screws 28a or the like to the floor of the room.

By the above construction the upright 19, when disposed in the socket 28 and pocket 21 may be securely held therein against rotation by the rib 22 and held securely in place by the lock nut 24 engaging the underside of the fillet 20, and by the nut 26 and lock nut 27 engaging socket 28. The upright 19 is also provided with adjustable collar 18 as in Fig. 2 on which rests the T head 14 of the arm 13 which carries the seat 17, which arm may be swung as shown in Fig. 1 from position to bring the seat in the L-shaped bay formed between the side of the sink and the drain board, or may be swung into inoperative position under the sink.

I do not limit my invention to the exact forms shown in the drawing, for obviously changes may be made therein within the scope of the claims.

I claim:

1. In combination, a sink having a pocket on its underside disposed adjacent one front corner, a drain board extending from the side of the

sink adjacent the pocket having its rear edge disposed flush with the rear edge of the sink and having its front edge inset from the front edge of the sink and forming with the side of the sink an L-shaped bay; an upright engageable with said pocket; and a horizontally swingable seat carried by said upright and movable into position under the sink and into said bay.

2. In a combination as set forth in claim 1, said sink having an apron; and said pocket being formed between the apron and the side of the sink.

3. In a combination as set forth in claim 1, said pocket having a transverse rib at its inner end receiving a corresponding slot in the end of the upright.

4. In a combination as set forth in claim 1, a floor plate below the pocket having a socket; and said upright having threaded ends carrying lock nuts for maintaining the upright engaged in the pocket and socket; and means in the pocket for preventing the upright from turning.

5. In a combination as set forth in claim 1, means for adjusting the elevation of the seat with respect to the sink.

6. In combination, a sink having pockets on its underside disposed adjacent its front corners, drain boards extending from opposite sides of the sink having their rear edges disposed flush with the rear edge of the sink and having their front edges inset from the front edge of the sink and forming with the sides of the sink L-shaped bays; an upright engageable with either of said pockets; and a horizontally swingable seat carried by said upright and movable into positions under the sink and into the related bay.

7. In a combination as set forth in claim 6, a floor plate having a socket adapted to be mounted at a point equi-distant from both pockets; and a single upright having its lower end offset to engage the socket whereby the one upright may be engaged with either pocket.

8. A sink, having a pocket on its underside disposed adjacent one front corner; and a drain board extending from a side of the sink adjacent the pocket and having its rear edge disposed flush with the rear edge of the sink and having its front edge inset from the front edge of the sink and forming with the side of the sink an L-shaped bay.

9. In a sink as set forth in claim 8, said sink having an apron; and said pocket being disposed between the apron and the side of the sink.

10. In a sink as set forth in claim 8, said pocket having a transverse rib at its inner end.

11. A sink, having pockets on its underside disposed adjacent its front corners; and drain boards extending from opposite sides of the sink and having their rear edges disposed flush with the rear edge of the sink and having their front edges inset from the front edge of the sink and forming with the sides of the sink L-shaped bays.

FRED WILLIAM MEYER.
